[57] CLAIM

The ornamental design for an adjustable holder for a gas torch, as shown and described.

DESCRIPTION

FIG. 1 is a perspective view of an adjustable holder for a gas torch showing my new design, the broken line showing of a gas torch being for illustrative purposes; FIG. 2 is a left side view thereof, with a right side view being a mirror image thereof;

FIG. 3 is a back view thereof;

FIG. 4 is a front view thereof;

FIG. 5 is a top view thereof; and,

FIG. 6 is a bottom view thereof.

FIG. 1

FIG. 2

FIG. 3

FIG. 4

FIG.5

FIG.6
